WIRE CONTAINER

Jay W. Cook, Detroit, Mich., assignor to The C and W Wire Container Company, Detroit, Mich., a corporation of Michigan

Application January 8, 1932. Serial No. 585,540

2 Claims. (Cl. 206—59)

The present invention pertains to a novel combination of wire container and dispenser, and more particularly to a container of the carton type. The principal object of the present invention is to provide a container of a construction whereby the wire or other cable may be drawn therefrom with a continuous or other longitudinal movement in an efficient manner without attention on the part of the workmen in installing or putting the wire into use, and further to incorporate in such container, guiding means so arranged as not to interfere with or necessitate a change in the usual methods of or regulations pertaining to the manufacture of cartons or containers for the purpose, or in the use of such containers as cartons for holding and enclosing coils of wire while being transported or handled.

A further object of the present invention is to provide a carton or container with wire guiding means through which the wire may be drawn centrally of the carton and whereby the wire is guided and directed regardless of the direction in which the wire is pulled from said guiding means, thereby preventing kinking or binding of the wire as it leaves the coil within the container.

With the above and other ends in view, the invention consists in the matters hereinafter set forth and more particularly pointed out in the appended claims, reference being had to the accompanying drawing in which

Figure 1 is a perspective view of a box, carton or container with a coil of wire or cable therein and illustrative of the manner in which the wire is guided as it is drawn therefrom;

Fig. 2 is a transverse, central section through the container, drawn to a reduced scale and showing guides brought together;

Fig. 3 is a similar section through the container showing guides separated;

Fig. 4 is a plan view of a blank from which the box or carton is formed;

Fig. 5 is a plan view of a blank forming an interior top wall of the box, and

Fig. 6 is a blank for forming an interior, central tube or cylinder.

Reference to the several parts of the device embodying the invention will now be made by the use of like reference characters designating corresponding parts throughout the several views.

While the device as illustrated is shown as provided with guiding members integral with the box or carton, it will be understood that these members may be formed separately therefrom and subsequently attached thereto, or their use dispensed with, without departing from the main

invention, the construction shown, being merely illustrative of one embodiment of the invention.

The blank from which the box or carton is made and as shown in Fig. 4, comprises a rectangular bottom section 1, a pair of side walls forming flaps 2 extending from opposite edges of the bottom section, a pair of end walls forming flaps 3 extending from the other edges of said bottom, and reinforcing flaps 4 extending from the ends of the flaps 3, these parts when properly folded and secured in any suitable manner, forming the bottom, side and end walls of a rectangular box, the flaps 4 being separated from the ends of the flaps 2, by slits 6 to permit of such folding. The blank may also be formed, as shown, with triangular flaps 5 extending from the outer edges of the side flaps 2 to fold over the top of the box, and for the purpose hereinafter set forth.

The blank 7 shown in Fig. 6, is of rectangular form with a plurality of tabs 8 extending from one of its longitudinal edges, and in making up the carton, this blank is rolled into the form of an open ended tube or cylinder, with said tabs 8 extended outwardly from its lower end 75 and glued or otherwise secured to the bottom 1, centrally thereof, to form a central tubular spindle or shaft within the box, to engage within the axial opening of a coil of wire 15 to be placed in the box and held centrally in the box, as illustrated in Fig. 1. The top of this box is formed by the rectangular blank 9, shown in Fig. 5, this blank having a circular opening 10, the end portions 11 being folded downwardly to lie against the end walls 3 of the box with the portion 9 80 extending across and closing the upper end of the box with the opening 10 therein concentric with the upper end of the center tube or cylinder 7 and spaced therefrom, the diameter of said opening being greater than the diameter of the tube to provide a space all around the upper end of the tube between it and the edge of the opening, said tube being of a length to extend up the full depth of the box with its upper end 85 in the plane of the lower side of the cover wall 9. 90

When the coil 15 is in place within the box and sleeved over the tube 7, the free end of the coil may be extended through the annular space between the upper end of the tube and the edge of the opening in the top wall of the box, so 105 that when this end of the wire is pulled outwardly, the wire of the coil which is put under tension by such pull and is shortened in its diameter thereby, will contact or close about the tube 7, which will stop such shortening or kink- 110

ing, and the turn will form a long spiral, free from the other turns of the coil, and will pass freely out through this annular opening without kinking or binding, said opening acting as a 5 guide for the wire as it passes therethrough, the wall 9 preventing the coil from becoming disengaged from the central post or tube 7 upon which the coil is sleeved.

To form a further guide for the wire as it is 10 drawn out, so that no matter in which direction the wire is led laterally from the box, the wire will not become kinked or bound and will pull out freely, the two flaps 5 which are adapted to be folded toward each other over the top of the 15 box, are provided with openings or eyes 13 reinforced with eyelets 14 adjacent their inner angles, and through which eyelets the wire is passed after passing through the annular opening around the tube 7. The flaps are of such a 20 length that they may overlap at their ends and therefore these ends are raised above the top wall of the box when the wire is being drawn through their eyelets and these eyelets will be located in alignment with the axis of the tube 7. The 25 wire is therefore guided axially of the coil as it is pulled therefrom and prevented from binding, no matter in which direction it is led laterally after passing through the eyelets.

These flaps 5 are preferably so connected to the 30 box along the opposite side edges thereof, that they may be folded flat down upon the top 9 of the box, their inner ends or angles being overlapped when so folded, or these end portions may be bent downwardly and inserted in the upper 35 end of the tube 7. These flaps 5 therefore, in no way interfere with the use of the box, as an ordinary carton in which such wire coils are usually shipped, and the form of the present box is such that it may be formed up from a blank, with or 40 without said flaps 5.

The present device therefore serves all the purposes of the ordinary box for holding a wire coil during transportation, and in addition serves as a holding and guiding means so that the wire may be pulled directly from the coil while contained in the box, thus doing away with the necessity for placing the coil upon a reel, or guiding or unwinding the wire by hand.

While a specific embodiment of the invention has been illustrated and described, it will be understood that various changes in the construction may be made within the scope of the appended claims, without departing from the spirit of the invention, and such changes are contemplated.

Having thus fully described my invention, what I claim is:

1. In a holding and dispensing container for a coil of wire comprising a rectangular box having bottom, side and top walls, said top wall being formed with a central opening, a tubular member secured at its lower end to the bottom wall of said box centrally thereof with its upper end adjacent said opening and spaced from the edge thereof to form an annular outlet opening 100 for an end of the wire of said coil, and a flap on said box having an opening in axial alignment with said tubular member and through which opening the end of said wire is led and guided.

2. A holding and dispensing container for a coil of wire, comprising a rectangular box having a top wall formed with an opening centrally thereof, and a pair of flaps connected to opposite sides of said box to swing thereon toward each other to bring their adjacent ends in overlapping relation, said flaps each being formed with a guide opening adjacent its free end.
